UNITED STATES PATENT OFFICE

2,099,528

BEER TAP ADAPTER

James McAdams, Chicago, Ill.

Application September 26, 1935, Serial No. 42,205

3 Claims. (Cl. 225—3)

This invention relates to means for drawing beer from barrels, kegs or the like, and is particularly intended as an adapter or attachment to be used in connection with beer taps or as a part of such taps. Taps are well known and are made in a variety of forms. They provide means for admitting air or gas under pressure to the barrel for forcing out the beer or other liquid and also provide means for inserting a tube or pipe commonly known as a "tap rod or tube" into the barrel for withdrawing the beer therefrom, such tube being usually connected with a pipe or hose leading to the cooler. The pipes or conduits leading from the beer barrel, including the cooling coils, should be frequently cleaned in order to provide good clean beer. It is possible to clean the coils even when the beer barrel is under pressure, by shutting off the tap rod valve and disconnecting the hose therefrom. Consequently this is often done and the tap rod is left without cleaning for indefinite periods. In accordance with the present invention I provide means whereby the tap rod or tube may be inserted into the barrel or withdrawn therefrom when the barrel is under pressure, without losing the pressure or permitting the discharge of any appreciable amount of the contents of the barrel.

The objects of this invention are to provide an improved adapter or device for accomplishing the above purposes in a simple and efficient manner; to provide an adapter or attachment which may be readily applied to beer taps such as are now in common use which may be cheaply made and which will be efficient in permitting the insertion and withdrawal of the tap rod without losing pressure; to provide a beer tap adapter for the purposes set forth which will have comparatively few parts and which will have a relatively smooth and unobstructed interior so that bacteria will not be apt to collect therein and also so that the device may be readily cleaned or sterilized and to provide such other advantages and improvements as will appear more fully hereinafter.

In the accompanying drawing illustrating a commercial form of my invention,

Figure 1 is a side view showing a barrel and tap with my adapter applied thereto, parts being shown in section;

Figure 2 is a side view showing the parts in position after the tap rod has been removed; and

Figure 3 is a sectional view taken on the line 3—3 of Figure 1.

The barrel 4 is shown with a tap 5 of any ordinary or preferred form of construction, this tap having the usual side connection 6 and hose or

pipe 7 for supplying air or gas under pressure to the interior of the barrel. The tap also has a locking nut 8 for attaching it to the barrel fitting and is provided with a threaded portion 9 for receiving a packing washer or gasket 10 and nut 11 or gland 11 having a handle 12 for turning the same.

The tap rod or tube 13 ordinarily extends downwardly through the tap to approximately the bottom of the barrel when the tap is in operative position and a tight closure or connection is made between the upper end 9 of the tap and the rod by means of the gland and packing 10.

In accordance with my invention I provide a valve body or fitting 14 which is threaded at 15 to 15 engage with the threaded upper end 9 of the tap. The upper end of the valve or adapter body 14 is recessed at 16 to receive the packing 10 and is provided with a shoulder 17 for engagement with the packing. The upper end is also threaded at 18 to receive the nut or gland 11 as readily seen from Figure 1. When my adapter is applied to the usual tap the packing or washer 10 and nut 11 are removed from the tap and placed in the upper end of the body as shown.

The tap rod 13 may then be inserted through the valve body 14 and the tap and into the barrel in the usual manner and the packing be tightened in order to prevent any leakage around the rod.

In order to prevent discharge of gas or liquid from the barrel, the valve body has a valve seat 19 at the top thereof which is adapted to be engaged by a ball 20 when the valve rod is removed. The ball 20 may be made of cork rubber, rubber composition or any other suitable material, preferably of a light and yielding character so that it may be readily forced against the seat 19 by the gas pressure.

The valve body 14 has a lateral projection 22 which forms a side chamber or recess for receiving the ball 20 when it is out of closing position. Curved side rails or guides 21 serve to guide the ball from its closing position as shown in Figure 2, to its normal or inoperative position as shown in Figure 1. The projection 22 is threaded to receive a plug 23 to close the opening through which the ball or valve 20 may be inserted and removed as for cleaning or the like.

When the keg 4 is tapped and the tap rod 13 inserted in the usual manner the packing 10 is 50 tightened and air or gas under pressure may be admitted through the supply pipe or hose 7, thus placing pressure on the contents of the barrel. The beer or other contents of the barrel may then be drawn off through the tap rod and out through 55

the pipe 25 being controlled by the valve 24. When it is desired to clean the tap rod or conduits connected therewith, the packing may be loosened and the rod withdrawn and thereupon the pressure on the ball or valve 20 will cause it to move up the guideway and engage with the seat 19, thus immediately closing the outlet of the barrel and preventing the escape of gas or pressure. In order to insure the upward movement 10 of the ball when the rod is removed, it will be noted that the bore through the fitting is made but little larger than the rod so that the gas entering at the bottom of the bore will immediately strike or act upon the ball 20 to force the same upwardly against the valve seat. In actual practice I have found that the valve will close with as low as five pounds pressure in the barrel even when using balls formed of rubber or rubber composition. After the rod has been cleaned it may 20 be returned and the ball will be pushed away from the seat and into the lateral part of the chamber so that the rod may pass down into the barrel in the usual manner.

It will be readily seen that by means of my improved adapter or control device the tap rod may 25 be removed and replaced at any time without losing pressure in the barrel or container. While I have shown a preferred and operative embodiment of my invention it will be noted that changes may be made in the same to adapt the device to different forms of taps or for other 30 conditions or purposes or the tap and my improvement may be combined in one structure, and therefore I do not wish to be limited to the exact construction herein shown and described 35 except as specified in the following claims, in which I claim:

1. Means for use with a tapping tube for beer barrels to prevent escape of gas when the tube is withdrawn, comprising a substantially tubular fitting having a central bore, means at one end of 40 said fitting for connecting it with the barrel, means at the opposite end of the fitting for making a tight closure between the fitting and the tube, said fitting having a lateral projection pro-

viding a recess for a valve ball said recess being open at the outer end thereof, means for closing the outer end of the recess, a valve seat at the upper end of the bore through said fitting, a valve ball in said fitting, and integrally formed curved 5 guide members for guiding the ball from its normal inactive position in said recess to the valve seat when the ball is moved upwardly by gas pressure, the arrangement being such that the ball may be readily removed for cleaning or replacement without removing the tube from the fitting.

2. A device of the character set forth, comprising a body portion adapted to be attached to the outlet of a barrel exteriorly thereof and having 15 an opening therethrough for permitting the insertion and removal of a tapping tube, said opening being enlarged at one side only to provide a valve chamber, a spherical valve member mounted in said chamber and adapted to close said 20 opening, said chamber having a hole in the side thereof for inserting and removing the valve member, a closure plug for said hole, and integrally formed means in said body for guiding the valve member from open position to closed position. 25

3. A device for the purposes set forth, comprising a valve body formed of a single casting having threads at one end for engagement with a beer tap and having a recess at the opposite 30 end, packing in said recess, a threaded gland engaging with threads in said recess for tightening the packing, said body having a longitudinal passageway for receiving the usual tap rod, said passageway being slightly larger than the rod, 35 a valve seat at the upper end of the passageway, integrally formed curved guides in said body, a ball valve engaging with said guides and adapted to engage with the valve seat, said body having a lateral chamber for receiving the ball valve when 40 in open position and having a hole in the side thereof for inserting and removing said ball valve, and a plug for closing said hole.
